UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PRODUCTION OF MOTOR FUEL

No Drawing.

Application filed March 17, 1926. Serial No. 95,500.

This invention relates to improvements in methods for producing motor fuel, and refers more particularly to the production of motor fuels having high "antiknock" and combustion retarding properties.

In the past few years, there has been considerable development work done along the line of producing a motor fuel in which the fractions would be uniformly consumed in burning, thus resulting in a more efficient operation of an internal combustion engine as distinguished from the present readily explosive mixture sold as motor fuels, which cause detonation in an automotive engine, which results in a loss of power and efficiency.

The present invention is directed to a process for producing a motor fuel possessing high antiknock properties.

I propose to take low temperature coal tar and subject same to cracking conditions of temperature and superatmospheric pressure for the purpose of producing an overhead distillate containing gasoline or similar motor fuels of high antiknock properties. These overhead products contain nitrogen compounds which have high antiknock properties, likewise phenolic, also oxidized hydrocarbons blended with a high percentage of unsaturated hydrocarbons and aromatic hydrocarbons.

These overhead distillates produced by cracking low temperature coal tar, contain a large portion of lighter fractions suitable for use as motor fuel. I separate these fractions in any obvious manner by means of fractionation or the like.

Using as a base straight run gasoline which may be defined as the condensed overhead product of the distillation of crude oil, I may blend regulated portions of said motor fuel produced by cracking low temperature coal tar to produce a blended product suitable for use as a motor fuel, preferably in a high compression engine which possesses high antiknock properties. It may be particularly pointed out that the motor fuel produced in accordance with the present invention will operate much more efficiently in a high compression engine than in a low compression engine where the ratio is say, $4\frac{1}{2}$ to 1 instead

of 6 to 1 and higher, although it is to be understood that I do not in any way wish to limit myself to the use of this fuel in a motor having any specific compression.

I have found that the proportions may be 55 from say 15 to 20% of the overhead product of cracking low temperature coal tar, to 80 to 85% of straight run gasoline which will produce a motor fuel, possessing these desirable antiknock properties, although it is to 60 be understood that I do not in any way wish to limit myself to any particular proportions, as it may be found advantageous to materially increase or decrease the relative proportions as above illustrated.

I have referred above to the use of straight run gasoline as the base. It is to be particularly noted that I may employ as a base a cracked gasoline produced from petroleum oils, or a mixture of cracked gasoline and straight run gasoline, both produced from petroleum oil.

I claim as my invention:

1. A motor fuel characterized by its antiknock properties comprising a pressure distillate produced by cracking low temperature coal tar blended with a greater quantity of straight run gasoline obtained from the distillation of crude petroleum oil.

2. A motor fuel characterized by its antiknock properties composed of pressure distillate produced from the cracking of low temperature coal tar and straight run gasoline obtained from the distillation of crude petroleum, the ratio of straight run gasoline to pressure distillate being in excess of three to one.

3. A motor fuel characterized by its antiknock properties comprising a pressure distillate produced by cracking low temperature coal tar blended with gasoline obtained from petroleum.

4. A motor fuel characterized by its antiknock properties comprising a pressure distillate produced by cracking low temperature coal tar blended with a greater quantity of gasoline obtained from petroleum.

5. A motor fuel characterized by its antiknock properties comprising pressure distillate produced from the cracking of low

temperature coal tar and gasoline obtained from petroleum, the ratio of gasoline to pressure distillate being in excess of three to one.

5 6. A non-detonating fuel for high compression motors, comprising a blend of cracked gasoline with regulated quantities of the cracked overhead product of low temperature coal tar distillation.

10 7. A motor fuel possessing desirable anti-knock properties comprising a blend of from 15% to 20% of the overhead product of cracking coal tar to 80% to 85% of straight run gasoline.
